UNITED STATES PATENT OFFICE

THOMAS E. BREWSTER, OF GRAND RAPIDS, MICHIGAN

COMPENSATING DIVISION SHEET

Application filed June 21, 1929. Serial No. 372,556.

This invention relates to a compensating division sheet or separate filler pad for use in so-called visible record books of the ring or prong-type wherein leaves or "inserts" 5 are held in lapped layers or series with the lower horizontal margin of each insert visible on one face of the layer, and the upper horizontal margin of each insert visible on the other face of the same layer such visible 10 margins being used for written headings identifying and differentiating the particular character of the record entries on each leaf or insert when the book is open and such layer or series in view, the said layers or 15 series being separated by division sheets having index tabs attached to identify each layer or series adjacent thereto.

When a series of inserts is so arranged, the thickness of the layer is practically uniform 20 from a central point in the series to a point distant from each extremity the height (width) of an insert of the size composing the series at which point the layer decreases in thickness progressively in steps the thickness 25 of an insert until but one thickness of insert remains at the extremities of the series (top and bottom of the book). As a result of this tapering, the writing surface of each layer is non-level, curving toward 30 either cover of the book which may be under the writing surface at the upper and lower extremities thereof.

The purpose of this invention is to correct the above defect, now present in all such 35 visible record books, by providing a division sheet built up with cemented leaves of graduated widths, lapped in the same direction and at the same intervals as the record inserts in the series adjacent to such division 40 sheet, thereby filling the vacant space resulting from the tapering above described with the built-up portion of the division sheet, thus equalizing the thickness of each layer, and producing a writing surface practically level from top to bottom, regardless 45 of the quantity of layers and division sheets under the surface written upon.

Inasmuch as a built-up division sheet completely cemented loses desirable flexibility, 50 an alternative construction is offered in the

separate filler pad or "levelizer", the leaves of which are cemented near the binding edge, and with a cover sheet added to the built-up or uneven side of the pad to protect the interior portions from dislodgment and their lapped edges from friction against or interference with the edges of the record inserts in the compensated layer when paging the book. A particular advantage of this 55 separate filler pad is that it can be inserted wherever necessary or eliminated from the book when the absence of record inserts at such position in the book makes it unnecessary; and it can be added to record books 60 now in use without discarding the original 65 division sheets, and cemented thereto if desired.

These pads can be easily constructed by assembling a certain quantity of blank inserts 70 usually of the same size and thickness as the record inserts in the layer to which the pad is to be applied, placing these blank inserts in the same position relative to each other as they would occupy in a regular series as record inserts, cementing them together from 75 top to bottom only near the binding edge, cutting the cemented assembly in half horizontally, cementing in the same manner a full size blank insert over the uneven or built-up side of each half with the margin of 80 this additional insert extended beyond the other inserts in the pad to form the one-sheet thickness or apex of the wedge (viewing the 85 pad in vertical cross-section compressed evenly). The two halves of the combined assembly provide compensation for vacancy at top of one layer and bottom of another, being exactly alike.

An understanding of the invention for the 90 attainment of the ends stated, as well as others at this time not specifically enumerated may be had from the following description taken in connection with the accompanying drawing, in which,

Fig. 1 is an edge view of a record book 95 to which my invention is applicable, the view being of the open or front edge of the book.

Fig. 2 is a similar view of the book having 100

the division sheets of my invention applied thereto.

Fig. 3 is an edge view of the division sheet of my invention.

5 Fig. 4 is a perspective view thereof.

Fig. 5 is an end elevation of a record book of the type to which the invention is applicable.

10 Fig. 6 is a perspective view of a modification of the invention showing separate filler pads which may be applied in conjunction with the regular division sheet, and

Fig. 7 is a longitudinal vertical section on line 7-7 of Fig. 6.

15 Like reference characters refer to like parts in the different figures of the drawing.

The record book to which my invention can be applied may be of well-known construction including spaced covers 1 and 2 connected by a flexible back 3 so that the covers 20 may be opened and having ring or prong devices, indicated at 4, with which the loose leaves of the book are adapted to be connected, the leaves at one edge having openings to pass said rings 4, the rings being of a 25 type capable of being opened to pass through the openings in the edges of the leaves or inserts.

30 A series of leaves or inserts, indicated at 5, is adapted to be bound in the book between the covers and said leaves are in width but a fraction of the distance between the upper and lower edges of the record book covers. The leaves overlap each other for a considerable portion of their width but each leaf or 35 insert at its lower edge on one face of the series and at its upper edge on the other face of the same series has an exposed portion on which indicia of the written record on the leaf may appear, to indicate what the leaf 40 refers to, and all the indicia on all the leaves will be presented for inspection when the record book is opened above a series of the leaves or inserts.

45 It is evident that as thus assembled there will be, at both the upper and lower ends of the record book, in a series of leaves 5, a progressive reduction in thickness, as indicated at 6, by reason of the number of thicknesses of leaves decreasing at both the upper 50 and the lower edges of the book. The series of leaves are separated by division sheet 7, located between each series and between the outside series and the covers 1 and 2. With 55 a plurality of the series of leaves between the covers 1 and 2 of the book there is a tapering of the thickness of the material between the covers nearly to a point at both the upper edges of the book as shown in Fig. 1 and with 60 a consequent bending of some of the division sheets 7.

In my invention the division sheets indicated at 7 are replaced by other division sheets made in accordance with my invention. 65 Such division sheets indicated at 8 in Figs.

2, 3 and 4, comprises a plane sheet having a plurality of lengths of paper 9 cemented at one side and at one end of the sheet, and a similar series of lengths of paper 10 cemented to each other and to the opposite side of the sheet at the other end. These lengths of paper 9 and 10 are of varying widths, the widest being in direct contact with the sheet 70 8 and cemented thereto along a narrow strip adjacent to the openings shown and the next widest similarly cemented to the widest and so on, whereby the lengths of paper 9 and 10 when attached to the division sheet present a stepped construction fully appearing in Figs. 3 and 4. The amount that the innermost widest length 9 of paper is wider 75 than the one next adjacent is equal to the amount that any of the record sheets 5 extends beyond the sheet next above, that is, the amount of the exposed upper edge portion 80 of the record sheet in contact with lengths of paper 9, and the exposed lower edge portion of the record sheet in contact with lengths of paper 10.

When the division sheets 8 are located in 90 the book between adjacent series of record sheets 5, the built-up stepped parts 9 and 10 compensate for and practically fill the space left vacant in the ordinary construction as shown in Fig. 1 due to the running out of 95 the material of the record sheets 5 at the upper and lower edges of the book. Above the lower cover 1 of the book a division sheet 8a is used which has only the stepped series 100 of lengths of paper 9a secured at its lower end and upper side; and under the upper cover 2, a sheet 8b is used which is equipped only with the step series of lengths of paper 10a at the upper end and under side of the sheet. 105

It is, of course, to be understood that the 110 number of lengths of varying widths of paper 9 and 10 used will be dependent upon the size of the record sheets 5, and different weights or thickness of record sheets 5 will be compensated with paper 9 and 10 of the same weight or thickness. But in any case there can be 115 constructed division sheets of the character described which will fully compensate for the reduction in thickness in a series of overlapping record sheets at the upper and lower edges of the series and eliminate the undesirable narrowing of the body of the record book between the covers at its upper and lower edges. 120

125 It should be noted that the engagement of the edges of the record sheets with the exposed edges of the parts 9 and 10 will serve to hold the record sheets against angular movement on the connecting rings 4. The connection of the record sheets 5 with the rings 4 is a loose one and such sheets are likely to move around and drop down to a position out of direct alignment with the upper and lower edges of the covers, whereas 130

the division sheets of my invention serve to correct this tendency.

Instead of attaching a series of lengths of paper 9 and 10 of different widths at the opposite sides and ends of the division sheets such as 8, 8a and 8b, a filler equivalent thereof may be used. The filler consists of a series of lengths of paper 11 of different widths located above each other, in stepped relations 5 the same as the parts 9 are thus located, and the same may be cemented together their full lengths or, preferably, only at one end. This cementing and joining together of the parts at one end alone is desirable in order to retain the flexibility of the paper which is lost to a very large degree by cementing several 10 thicknesses of paper together completely. This cementing of the parts 11 at one end is indicated at 13 in Fig. 7. Also the staggered side of the filler thus made may be covered by a covering sheet 12 extending beyond the edges of the thicknesses of paper as shown, and the ends of the parts 11 have the same openings that the division sheets 15 and the record sheets have for passing the securing rings 4 therethrough. Fillers of this kind may be used next to division sheets like the sheets 7 in Fig. 1 at either side thereof, as an equivalent for the parts 9 and 10 20 connected directly to a division sheet.

The construction while simple is very practical and serviceable and has so proved in practice. The invention is defined in the appended claims and is to be considered comprehensive of all forms of structure coming 25 within their scope.

I claim:

1. A filler for the purposes described comprising, a plurality of lengths of thin sheet 30 material of progressively decreasing widths located one over the other with the widest of said lengths of material at the bottom and the narrowest at the top, one of the edges of all of said lengths of material being cemented 45 together at one end.

2. A construction containing the elements in combination defined in claim 1, combined with an additional length of thin sheet material located over the upper side of the 50 filler and cemented at one end thereto, said additional length of material being wider than the lowermost widest length of first-mentioned lengths of material and extending beyond the same.

3. A filler for the purpose described comprising, a plurality of sheets of material of 55 progressively decreasing widths located in superimposed relation, means at one edge of the sheets for permanently joining them 60 each to the next, the remaining portions of the sheets being unconnected, and means at the same edge of the sheets for fixing them in a book.

4. A filler for the purpose described comprising, a plurality of sheets of material of 65

progressively decreasing widths located in superimposed relation, said sheets having holes near one edge whereby they may be fastened in a book and means for joining small corresponding portions of each sheet together, said joining means being adjacent the holes. 70

5. A filler for the purpose described comprising, a plurality of sheets of material of decreasing widths located in superimposed relation, and means near an edge of the sheets for permanently joining them to each other, the remaining portions of the sheets being unconnected, said sheets having holes therein near said edge whereby they may be fastened in a hook. 75 80

In testimony whereof I affix my signature.
